SELF-CLOSING SAFETY PIN

John A. Benditt, Philadelphia, Pa.

Application June 24, 1949, Serial No. 101,161

6 Claims. (Cl. 24—161)

1

This invention relates to a novel construction of safety pin which, due to its inherent resiliency, is spring biased to a closed position and capable of being opened by the exertion of a manual pressure thereon.

Still another object of the invention is to provide a safety pin having means for receiving and shielding the piercing pointed end of the safety pin, and which pointed end is disposed in a shielded position when the pin is held normally closed by its inherent resiliency so that should the pin be accidentally swallowed by a child the possibility of serious injury resulting therefrom is reduced to a minimum.

Still a further object of the invention is to provide a novel construction of safety pin which may be manually grasped and squeezed at the end thereof remote to the piercing point for opening and holding the safety pin in an open position while it is passed through portions of fabric or other elements to be connected thereby and which, upon release of said end of the safety pin will permit the pin to automatically resume a closed position and to maintain such closed position until reopened by a positive force exerted on said end thereof which is remote to the piercing point and point shield of the pin.

Various other objects and advantages of the invention will hereinafter become more fully apparent from the following description of the drawing, illustrating a presently preferred embodiment of the invention and wherein:

Figure 1 is a side elevational view of the safety pin, on an enlarged scale;

Figure 2 is a bottom plan view thereof, likewise on an enlarged scale;

Figures 3 and 4 are cross-sectional views of the safety pin taken substantially along planes as indicated by the lines 3—3 and 4—4, respectively, of Figure 1 and on an enlarged scale with respect to Figure 1, and

Figure 5 is a sectional view taken substantially along a plane as indicated by the line 5—5 of Figure 3.

Referring more specifically to the drawing, the novel self-closing safety pin in its entirety and comprising the invention is designated generally 6 and is formed from a single strand of relatively heavy gauge resilient wire, designated generally 7 and a single pivot element, designated generally 8.

The intermediate portion of the strand 7 is bent to provide a spring coil 9 preferably of approximately one and one-half convolutions having corresponding legs 10 projecting from the

2

ends thereof in the same direction which are outwardly bowed relatively to one another and which are turned back upon themselves as seen at 11 to provide outer leg portions 12 which extend in the opposite direction to the inner leg portions 10. Said turned back portions 11 are disposed in crossed relationship, as best seen in Figure 2. The remote sides of the outer leg portions 12 are knurled or roughened on their outer sides as seen at 13 to afford a good finger grip, for a purpose which will hereinafter become apparent. Each of the outer leg portions 12 extend to beyond the intermediate spring coil 9 and the terminals of said leg portions 12 terminate in corresponding coils 14, each preferably constituting slightly more than one convolution and which coil portions 14 are normally spring biased outwardly and away from one another by the resiliency of the spring coil 9 and the leg portions 10, 11 and 12.

By exerting pressure as with the thumb and index finger against the outer or knurled sides 13 of the leg portions 12, the coils 14 will be brought into transverse alignment for receiving the pivot member 8 which may constitute a double headed pin or other pivot element but which preferably comprises a rivet, as best illustrated in Figure 3 one section of which is formed by a bearing sleeve 15 and the other section of which is formed by a pin or shank 16 which may be secured in the sleeve 15 in any suitable manner as by a press fit engagement therewith. The remote ends of the sleeve 15 and pin 16 are provided with integral heads 17 which are larger than the coils 14 for retaining said coils in engagement with the pivot member 8.

The parts 9 to 12, previously described, combine to form the actuating section designated generally A of the safety pin 6 and the remaining terminal portions of the strand 7 combine to form the clasp or pin section, designated generally B.

One terminal of the strand 7 which forms a continuation of the coil 14, formed by the lower leg portion 12, as seen in Figure 1, and which extends from the bottom of said coil 14 in a direction away from the actuating section A constitutes the fabric piercing pin portion 18 of the pin or clasp B and has a pointed free end 19.

The other terminal of the strand 7 extends from the top of the other coil 14 of the upper leg 12 likewise in a direction away from the actuating section A to form the guard portion 20 of the pin or clasp section B and which is longer than the pin or piercing section 18. Said guard section 20, adjacent its free end, is turned down-

wardly and back upon itself as seen at 21 and is provided adjacent the terminal thereof with an upwardly or inwardly bowed portion, designated generally 22, the extension or outer end of which is flattened and thereby widened as seen at 23. Said flattened or widened terminal portion 23 is split longitudinally and centrally as seen at 24 to provide a fork the two corresponding tines of which extend generally downwardly and are provided with upwardly or inwardly curved terminal portions 25. The pin or piercing member 18 and the guard portion 20 are bowed outwardly relatively to one another, as best seen in Figure 1.

The resiliency of the parts 9 to 12, constituting the actuating section A cause the leg portions 12 thereof to be spring biased away from one another and accordingly cause the extensions of said leg portions 12, constituting the pin or piercing member 18 and the guard 20 to be spring biased toward one another. The piercing point 19 is so disposed that under the normal biasing action of the actuating section A, said point 19 will enter the slot 24 of the fork 23 which thus forms a guide for said point and as seen in Figure 2, when the pin or piercing member is in engagement with the inner, tapered portion of the slot 24 the tip of the point 19 will be disposed adjacent the other, inner half 26 of the inwardly bowed guard portion 22 and which constitutes a shield for said point 19. With the pin or clasp section B thus disposed in its normal, closed position as seen in Figures 1 and 2, the upward or inward turned terminals 25 of the tines of the fork 23 will be disposed substantially parallel to the adjacent portion of the pin or piercing member 18 so as not to provide a protruding obstruction.

From the foregoing it will be readily apparent that when the safety pin 6 is to be applied to pieces of fabric, for example, not shown, the user places his or her index finger against the knurled surface 13 of the lower leg portion 12 and the thumb against the knurled portion 13 of the upper leg portion 12 and by exerting a squeezing pressure displaces said leg portions 12 toward one another thereby causing the convolutions 14 to turn relatively to the pivot 8 in opposite directions for swinging the pin or piercing member 18 downwardly and the guard member 20 upwardly or in directions away from one another, as illustrated in dotted lines in Figure 1 for exposing the point 19 of the pin or piercing member 18 and while thus holding the leg portions 12 under pressure and so that the parts 18 and 20 of the actuating section A will be in substantially the positions as seen in dotted lines in Figure 1, the piercing member or pin 18 is passed through and then back through pieces or portions of fabric or other elements to be secured together and when the point 19 is again exposed, pressure on the leg portions 12 is released thereby permitting the members 18 and 20 to be spring biased from their dotted line positions of Figure 1 back to their full line positions of Figure 1, in which last mentioned position the pin 6 is closed. It will thus be seen that the pin 6 is normally maintained in a closed position by the biasing action of the actuating section A so that there is no danger of the pin becoming accidentally unfastened and opened and to insure that the pin will at all times be closed unless opened by a positive pressure, as previously described.

Various modifications and changes are contemplated and may obviously be resorted to, without departing from the spirit or scope of the

invention as hereinafter defined by the appended claims.

I claim as my invention:

- 5 1. A self-closing safety pin comprising a single strand of resilient wire having an intermediate portion defining a spring coil, legs extending from the ends of said coil and from substantially diametrically opposite portions thereof in the same general direction, said legs being crossed and turned back upon themselves to provide corresponding outer leg portions extending back beyond said spring coil and each terminating in a coil portion, said coil portions being normally spaced from one another and being displaceable into alignment with one another by pressure exerted on said outer leg portions and in directions toward one another, a pivot element extending through said coil portions and on which said coil portions are pivotally mounted, said 10 spring coil and leg portions combining to form an actuating section of the safety pin, one terminal of said strand extending from one of said coil portions in a direction away from said actuating section and constituting a pin or piercing member and having a pointed terminal, the other terminal of said strand extending from said other coil portion in substantially diametrically opposite relationship to said piercing member and in a direction away from the actuating section and constituting a guard member, said guard member having a portion turned inwardly and back upon itself and terminating in an inwardly bowed portion constituting the terminal of said last mentioned strand end, the terminal part of said inwardly bowed portion being flattened and bifurcated to provide an outwardly opening guide slot disposed to normally receive a portion of the pin or piercing member, said pin or piercing member and said guard member being spring biased toward one another by the resiliency of said actuating section for normally positioning said pin portion in engagement with the slot of the bifurcated guard portion for retaining the safety pin in a normal closed position.
- 15 2. A self-closing safety pin as in claim 1, said pin or piercing member and said guard member combining to form the safety pin or clasp section of said safety pin.
- 20 3. A self-closing safety pin as in claim 1, said pin or piercing member and said guard member being outwardly bowed relatively to one another and being displaceable in directions away from one another and to an open position by a gripping pressure exerted on said outer leg portions of the actuating section.
- 25 4. A self-closing safety pin as in claim 1, said pin or piercing member and said guard member being outwardly bowed relatively to one another and being displaceable in directions away from one another and to an open position by a gripping pressure exerted on said outer leg portions of the actuating section, said outer leg portions of the actuating section being knurled on their outer sides to provide finger grips.
- 30 5. A safety pin as in claim 1, and the inner part of the inwardly bowed terminal of said guard member constituting a shield adjacent the inner side of which the point of the pin or piercing member is disposed when the pin or clasp section is in its normal, closed position.
- 35 6. A self-closing safety pin formed from a single strand of wire including longitudinally spaced end portions, one of said end portions constituting the intermediate part of said strand and forming an actuating section of the safety

pin, said other end constituting the terminals of said strand forming the pin or clasp section of the safety pin, aligned coil portions disposed between said safety pin sections, a pivot element rotatably engaging said aligned coil portions and retaining them against normal spring biasing movement away from one another, and said actuating section including outer portions adapted to be gripped and pressed toward one another for displacing the terminals of the strand, de-

fining the pin or clasp section, away from one another for opening the safety pin, said strand terminals being normally spring biased toward one another by the resiliency of said actuating section for normally retaining said terminals in engagement and the safety pin in a closed position.
